UNITED STATES PATENT OFFICE.

ELMER U. AMES, OF PHILADELPHIA, PENNSYLVANIA, ASSIGNOR TO H. BRINTON COMPANY, OF PHILADELPHIA, PENNSYLVANIA, A CORPORATION OF PENNSYLVANIA.

TRANSMISSION MECHANISM.

1,151,431.

Specification of Letters Patent. Patented Aug. 24, 1915.

Application filed September 23, 1914. Serial No. 863,180.

To all whom it may concern:

Be it known that I, ELMER U. AMES, a citizen of the United States, residing in Philadelphia, Pennsylvania, have invented 5 certain Improvements in Transmission Mechanism, of which the following is a specification.

My invention relates to improvements in mechanism particularly designed for use in 10 connection with knitting machines and is especially serviceable in "circular" machines in which the needle cylinder, or, in some types of machines, the needle cam-ring, requires a continuous circular movement, such for example as is required in 15 knitting the tubular leg portion of a stocking, and is given a reciprocating motion such as is necessary for knitting the toe or heel.

20 In knitting machines of the above mentioned types it is difficult to gain access to those parts of the mechanism which effect the above noted circular and reciprocating movements since said parts are on the in- 25 side of the frame, and heretofore if a part of said mechanism became worn or broken or failed to work properly, it was necessary to remove various other parts, one at a time, until the desired part was reached. This 30 required considerable time and often re- sulted in a disturbance of the adjustments of certain of the parts besides frequently necessitating the removal of the entire machine.

35 One of the objects of my invention therefore is to so construct a knitting machine of the above described type that those of its elements which effect the operation of the needle-controlling mechanism may be re- 40 moved from the machine proper in such manner as to permit of the easy removal and replacement of any of the separate elements; the arrangement and design being such that the driving means for the needle 45 controlling mechanism shall be durable and of simple construction. These objects and other advantageous ends I attain as herein- after set forth, reference being had to the accompanying drawing in which,

50 Figure 1 is a side elevation of my invention; Fig. 2 is a section taken on the line *a—a*, Fig. 1; Fig. 3 is a section on the line *b—b*, Fig. 2; and Fig. 4 is a perspective view of a modified form of one of the parts 55 of my invention.

In the above drawings, 1 is the knitting machine frame which forms a support for a shaft 2 on which is fixed a gear wheel 3 operable to actuate a needle cylinder or needle cam ring of any type of knitting machine head, one of whose parts must at certain times receive a continuous circular movement while at other times it requires a reciprocating movement. The shaft 2 and gear wheel 3 are therefore so driven as to alternately receive a continuous rotary and a reciprocating movement in a manner hereinafter described.

The frame 1 has an aperture 4 in one of its sides and in the opposite side also has a journal-box or bearing 5, for one end of a shaft 6. A cover plate 7 is detachably secured to the frame 1 by bolts 8 so as to extend over the aperture 4 and has a journal box or bearing 9 for the opposite end of the shaft 6, together with a sleeve portion 10 designed to rotatably receive within it the hub 11 of a pulley 12. The outside surface of said sleeve forms a bearing for a loose pulley 13, while the inside of said hub 11 forms a bearing for a rotatable shaft 14 having a pulley 15 secured to one end and a gear wheel 16 keyed to it adjacent its other end.

The gear 16 meshes with a gear wheel 17 which is freely rotatable on the shaft 6 and has a clutch face 18 designed to interlock with the face 19 of a clutch collar 20 slidably keyed to said shaft 6. A gear wheel 21 is fixed to the gear 17 and meshes with a gear wheel 22 formed on the inner end of the pulley hub 11. The end 23 of the clutch collar 20 is shaped to engage a clutch extension 24 on a gear wheel 25 which is freely rotatable on the shaft 6 and said gear meshes with the teeth 26^a of a segment 26 whose lower end has a bearing 26^b directly below its toothed portion, being mounted to oscillate on a shaft 27 supported in the frame 1.

A stud shaft 28 is rigidly secured to the cover plate 7 by means of a nut 29 and forms a support for a freely rotatable sleeve 30 having a crank 31, having an eccentric outline for driving apparatus forming no part of the present invention, there being a gear wheel 32 keyed on said sleeve 30 and meshing with the gear 16. The crank 31 has a crank pin 33 secured thereto by a nut 34 and extending through a slot 35 in the segment 26 so as to form a pivotal support for the end 110

bearing 36^a of a connecting rod 36. The other end of said rod forms a pivotal bearing for a pin 37^a connected to a projecting arm 37 on said segment 26 (Figs. 1 and 3).

5 In Fig. 1 of the drawings the member 31 is shown in the form of an eccentric having a strap 55 for actuating pattern mechanism or any other movable part of the knitting machine proper. It will be understood, 10 however, that this member 31 may be replaced in some instances by an ordinary crank arm 31^a having a crank pin 33 secured thereto as shown in Fig. 4. If this latter construction is adopted the motion of the 15 pattern means heretofore mentioned may be obtained from another source if this is desirable.

As a means for shifting the clutch sleeve or collar 20, I may provide two collars 38 and 39 adjustably secured to the sleeve 30 by means of set screws 38^a and having cams 40 and 41 whose inner actuating surfaces extend toward each other (see Figs. 2 and 3). A double arm lever 42 is pivotally mounted on a projection 43 on the cover plate 7 and has its upper arm in engagement with a groove 44 of the clutch collar 20 while its lower arm 45 forms a housing for two pins 46 and 47. These pins are normally held out of the path of the cams 40 and 41 by means of springs 48 and 49, although if either of them is moved into engagement with its respective shifting cam during rotation thereof the lever 45 will be 35 pushed to one side or the other and will be rocked on its pivot, thereby causing a sliding movement of the clutch collar 20. Therefore if the pins 46 and 47 are alternately moved into and out of engagement 40 with the shifting cams 41 and 42, the clutch collar 20 will receive a sliding movement alternately in opposite directions along the shaft 6, and will alternately engage the clutch extension 24 on the gear 25 and the 45 clutch portion 18 on the gear 17. The pins 46 and 47 are actuated by levers 50 and 51, which, in the present instance, are pivotally mounted on a rod 52 on the frame 1 and each has an arm 53 projecting rearwardly so as 50 to be actuated by any form of pattern means (not shown) which may be driven by the strap 55 of the eccentric 31 and timed to alternately move said pins. It will be understood however that any other suitable 55 form of mechanism may be employed to alternately move the pins 46 and 47 without departing from my invention.

The crank 31 has an extension 54 which is diametrically opposite the crank pin 33 and forms a balance therefor so as to cause even running of the several parts.

60 Motion is transmitted from the shaft 6 to the shaft 2 by two intermeshing beveled gears 56 and 58 respectively fixed to said shafts.

Assuming that the pin 47 has been moved by the lever 51 into engagement with the shifting cam 41 and that the latter has actuated the double arm lever 45 to move the clutch collar 20 into engagement with the 70 clutch face 18 (see Figs. 2 and 3), a suitable belt (not shown) serves to drive the pulley 15, shaft 14, and gears 16 and 17, and since the face 19 of the clutch collar 20 is in engagement with the clutch face 18 of the gear 75 17 said collar will be rotated. A continuous rotary movement is thus imparted to the shaft 6, gears 56 and 58 and eventually through the shaft 2 to the gear 3 which serves to actuate the needle controlling 80 mechanism.

When an alteration in the character of the fabric being produced is required, such for example as a change from the "round-and-round" knitting of the leg of a stocking, to 85 that necessary to produce a heel, the movement of the gear 3 is necessarily changed from a continuous rotary movement to a reciprocating movement. The pattern means is therefore so timed as to effect the shifting 90 of the belt from the pulley 15 onto the pulley 12 and also to move the lever 50 so as to cause movement of the pin 46 into engagement with the cam 40 with a resulting movement of the lever 45. This movement of 95 said latter lever actuates the clutch collar and brings the clutch face 23 into engagement with the clutch extension 24 on the gear 25. Motion will then be transmitted from the pulley 12 to the gears 22, 21, 17, 16 100 and 32, crank 31, and connecting rod 36 to the arm 37 on the segment 26 and since said connecting rod is moved by means of the crank pin 33, it will receive a reciprocating movement which it in turn imparts to said 105 segment 26. Hence the gear 25 which is in mesh with the teeth on said segment will receive a reciprocating movement which is transmitted to the clutch collar 20, shaft 6 and gears 56 and 58, thus causing reciprocation 110 of the gear 3 and of the needle actuating mechanism driven thereby. The driving mechanism above described will thus impart to the gear 3 either a continuous circular movement or a reciprocating movement.

115 It will be noted that the clutch mechanism and the means for adjusting the same may be removed as a unit from the machine merely by removing the bolts 8 and the pin 57 which secures the gear 56 to the shaft 6. The end of the crank pin 33 which extends into the connecting rod 36 is not secured thereto in any manner and may be freely removed when the cover plate 7 is taken off so that all the mechanism with the exception of the segment 26 may be quickly and easily withdrawn as a whole through the aperture 4 in the frame 1. This feature forms a very important part of the present invention since it enables a work- 120 125 130

man to easily and quickly repair or replace any of the several parts of the driving mechanism above described.

Another valuable feature of the invention resides in the improved arrangement and construction of the driving elements for the toothed segment whereby any undesirable twisting or unbalanced stress is avoided, for it will be noted that the toothed edge 10 26^a, the bearing 26^b and the bearings 36^a and 37^a of the connecting rod 36 are all in or immediately adjacent the plane of movement of the segment 26 (see Fig. 3) so that the line of action of the force which 15 moves the latter will lie in said plane. Moreover the crank 31 is positioned on one side of the segment 26 while the connecting rod 36 is positioned on the opposite side thereof with the result that the stresses on said 20 crank are in a great measure balanced and an even movement is imparted to said segment.

While I have described my invention as applicable to knitting machines it will be understood that without departing from my invention it may be used in connection with any other type of mechanism requiring a continuous rotary movement at one time and a reciprocating movement at another time.

I claim:

1. The combination of a frame having an aperture; a plate covering the aperture and detachably secured to said frame; an oscillatory segment on the frame; with mechanism supported by said plate including an element detachably connected to the segment, said mechanism being removable as a unit with the plate from the frame.

2. The combination of a supporting frame; actuating means; a member detachably secured to the frame; with operating mechanism for the actuating means supported by said member and removable therewith as a unit, from said frame, the actuating means and operating mechanism including a crank pin and a crank separable to permit the removal of said unit.

3. The combination of a supporting frame having an aperture; actuating means; a member detachably secured to the frame; with operating mechanism including reciprocating driving mechanism for the actuating means supported by said member and removable, as a unit, from the frame through said aperture.

4. The combination of a supporting frame having an aperture; actuating means; a cover plate for the aperture detachably secured to the frame; with operating mechanism for the actuating means including rotary and reciprocating driving mechanism supported by said plate, and removable, as a unit, from the frame through the aperture.

5. The combination of a supporting frame having an aperture; actuating means; a member detachably connected to the frame; clutch mechanism having a support in said member; clutch shifting mechanism supported by said member; and driving mechanism for the clutch and clutch shifting mechanisms also supported by said detachable member.

6. The combination of a supporting frame; actuating means; a member secured to said frame; a clutch shaft having one portion mounted in the frame and another portion mounted in said member; clutch mechanism on said shaft; a stud shaft on said member; means on said latter shaft for operating said clutch mechanism; and driving means for the clutch shaft mounted on said member, said member with the clutch shaft, and said mechanisms being removable, as a unit, from the frame.

7. The combination of a supporting frame having an aperture; actuating means, a cover plate secured to the frame; a clutch shaft having one portion mounted in said frame and another portion mounted in said cover plate; clutch mechanism on said shaft; a stud shaft on said plate; means on said latter shaft for operating the clutch mechanism; with driving means for said clutch shaft mounted on said plate, said plate being detachable from the frame and the clutch shaft, and said mechanisms being removable through said aperture.

8. The combination of a supporting frame having an aperture; actuating means; a member detachably connected to the frame; a clutch shaft having one portion supported in said frame and another portion mounted in said member; means operatively connecting said shaft and said actuating means; a clutch collar slidably keyed on said shaft; two gear wheels freely rotatable on said shaft and each having a clutch face designed to be engaged by said clutch collar; a third gear wheel secured to one of said gear wheels; a stud shaft for said member; a lever mounted on the member and operatively connected to said clutch collar; a sleeve rotatably mounted on said stud shaft; a gear and cams for operating said lever, mounted on said sleeve; an actuating device in engagement with one of said first mentioned gear wheels; mechanism operatively connecting said sleeve with said device; and means mounted on said member for driving the gear on said stud shaft, the other of said first mentioned gear wheels and said third gear wheel.

9. The combination of a frame having an aperture therein; actuating means; a plate covering said aperture; a clutch shaft having one portion mounted on said frame and another portion supported by said plate; mechanism operatively connecting said ac-

tuating means with said clutch shaft; a stud shaft supported on said plate; clutch mechanism on said clutch shaft; means for actuating the clutch mechanism and driving 5 mechanism supported by said plate for operating said latter operating mechanism and the clutch mechanism.

10. The combination of a supporting frame having an aperture; actuating means; 10 a member detachably connected to the frame; a clutch shaft having one portion supported in said frame and another portion mounted in said member; means operatively connecting said shaft and said actuating 15 means; a clutch collar slidably keyed on said shaft; two gear wheels freely rotatable on said shaft and each having a clutch face designed to be engaged by said clutch collar; a third gear wheel secured to one of said 20 gear wheels; a stud shaft secured to said member; a lever mounted on the member and operatively connected to said clutch collar; a sleeve rotatably mounted on said stud shaft and having a gear and cams mounted 25 thereon, said cams being operable to actuate said lever; mechanism mounted on said member for driving the gear on said stud shaft, the other of said first mentioned gear wheels and said third gear wheel; a segment 30 having teeth in engagement with one of said first mentioned gear wheels; and means connected to said sleeve for imparting a reciprocating movement to said segment.

11. The combination of a supporting 35 frame; a plate; a gear; a support for the

gear having a mounting in the plate; a segment mounted on said frame and operatively connected with the gear; means supported on the plate for moving the segment; and means for detachably connecting the 40 plate to the frame, the gear, gear support and segment moving means being removable, as a unit, with the plate.

12. The combination of a supporting structure; a gear; a segment mounted to 45 oscillate on said supporting structure and having teeth engaging said gear; a crank on one side of the segment; a connecting rod on the opposite side of said segment; means operatively connecting the crank and rod; 50 and means operatively connecting the rod to the segment.

13. The combination of a supporting structure; a gear; a segment mounted to 55 oscillate on said supporting structure and having teeth engaging said gear; a crank on one side of the segment; a connecting rod on the opposite side of said segment; means for pivotally connecting the crank and rod; and means pivotally connecting the rod to 60 the segment, both of said means being immediately adjacent the plane of movement of said segment.

In testimony whereof, I have signed my name to this specification, in the presence of 65 two subscribing witnesses.

ELMER U. AMES.
